UNITED STATES PATENT OFFICE.

JOSEPH H. CAMPBELL, OF PITTSBURG, PENNSYLVANIA, ASSIGNOR OF ONE-SIXTEENTH TO HENRY T. WILEY, OF BOSTON, PA., AND ONE-EIGHTH TO FRANK PATTERSON, OF BUENA VISTA, PA.

PROCESS OF AND APPARATUS FOR EXTINGUISHING FIRES.

SPECIFICATION forming part of Letters Patent No. 234,531, dated November 16, 1880.

Application filed September 27, 1880. (No model.)

To all whom it may concern:

Be it known that I, JOSEPH H. CAMPBELL, of Pittsburg, in the county of Allegheny and State of Pennsylvania, have invented a new and useful Improvement in Process of and Apparatus for Extinguishing Fires; and I do hereby declare that the following is a full and exact description thereof, reference being had to the accompanying drawings, and to the letters of reference marked thereon.

My invention relates to extinguishing fires by carbonic-acid gas; and it consists in the method of generating the said gas (without the commingling of two reagents, such as sulphuric acid and the carbonate of lime or soda,) by drawing air through a burning mass of charcoal, then cooling said commingled air and carbonic-acid gas, in which condition it is ejected upon the fire to be extinguished.

To enable others skilled in the art with which my invention is most nearly connected to make and use it, I will proceed to more fully describe it and the operation thereof.

In the accompanying drawing, which forms part of my specification, A represents a steam-boiler or air-blast device, to which is attached a pipe, B, which communicates with the lower part of an open furnace, C, charged with burning charcoal D.

The pipe B is provided with a device, E, known as a "steam-siphon," for causing a current through pipe B and drawing air through and carbonic-acid gas from the furnace C and forcing the combined air and carbonic-acid gas through said pipe B into the cooling device F, which consists of a casing divided into two compartments, H and I. The compartment H is furnished with a coil of pipe, J, which communicates with the pipe B and chamber I, to which is attached a hose furnished with a suitable nozzle for ejecting the carbonic-acid gas upon the fire to be extin-

guished. The coil of pipe in chamber H should be covered with cold water, for the purpose of cooling the carbonic-acid gas and air combined during its passage through said pipe to the compartment I of the cooling device.

The apparatus hereinbefore described may be modified in its construction without departing from the principle of operation thereof, and said apparatus or modified form of it may be mounted upon suitable running-gear for the purposes of a fire-engine used for extinguishing fires.

The form and construction of the apparatus hereinbefore described I leave to the skill and taste of the constructor.

By the process hereinbefore described I am enabled to generate carbonic-acid gas in unlimited quantities, and in a suitable condition for forcing it upon the fire to be extinguished, so that in the extinguishment of said fire the burning material will be cooled in the operation.

Having thus described my improvement, what I claim as of my invention is—

1. In extinguishing fires by carbonic-acid gas, the method of generating the gas without the commingling of two reagents, which consists in drawing air through a burning mass of charcoal, and then cooling the said air and commingled carbonic-acid gas, in which condition it is ejected upon the fire, substantially as set forth.

2. The apparatus consisting of the steam generator or blast A, pipe B, steam or air forcing device E, furnace C, and cooling device F, constructed, arranged, and operating substantially as herein described, and for the purpose set forth.

JOSEPH H. CAMPBELL.
